UNITED STATES PATENT OFFICE

2,415,765

CUSHION

R. Thur Schmidt, Chicago, Ill.

Application May 10, 1943, Serial No. 486,302

5 Claims. (Cl. 155—179)

1

This invention relates to cushions and particularly to cushions as used in chairs, beds and the like.

The particular object of this invention is to provide a cushion that is light in weight, yet sturdy, and durable.

Another object is to provide a cushion that may be easily dismounted in units that may be cleaned and made thoroughly sanitary.

Another object is to provide cushion structure that may be readily modified to form seats and backs of chairs, or rearranged to provide beds or the like.

And a still further object is to provide a cushion that is largely water-proof and non-absorbent so that, combined with its light weight and normally sealed interior air space, it is extremely buoyant.

Other objects and benefits will be disclosed in the following descriptions and drawings in which:

Fig. 1 is a perspective view of the metallic supporting structure;

Fig. 2 is a broken enlarged sectional view showing the contact of the central spring mounting with the base wire as will later be explained.

Fig. 3 is a front elevation view of the metallic supporting structure as it would appear on the section lines 3—3 of Fig. 1;

Fig. 4 is a cross sectional elevation view of a coil spring used in conjunction with the supporting structure as will later be explained;

Fig. 5 is a cross sectional view of the spring shown in Fig. 4 embedded in plastic material;

Fig. 6 is a broken top plan view of the central spring mounting;

Fig. 7 is a cross sectional view of the supporting structure shown in Fig. 3, attached to the spring member shown in Fig. 4 embedded in plastic material as will later be explained; and

Fig. 8 is a cross sectional elevation view of my cushion upholstered and mounted on a supporting member as will later be explained.

Now referring to the drawings, and at the outset to Fig. 1 I form a cushion supporting structure from spring alloy aluminum wire by attaching a base wire 10 to a top frame member 11 by welding therebetween a concave continuously looped spring 12. Cross wires 14 and 15 are attached to the top frame 11 by welding their ends thereto. This forms an aluminum spring wire supporting structure which may be placed on dual cross springs 16 and 17, held together and to a cup stamped member 18 by a bolt 19. The ends of the flat spring members 16 and 17 are

2

formed into supporting sockets 20 as clearly shown in Fig. 2.

The supporting structure as described is now inserted in a mold and embedded in plastic material such as ethyl cellulose or any other similar plastic which is flexible and somewhat rubberlike to form a member 21 as clearly shown in Fig. 7. A coil spring 22 is similarly placed in a mold and embedded in a plastic to form a member 23 as shown in Fig. 5. The member 23 is now attached in the center of the member 21 by fusing or vulcanizing fillet 24.

From the above description, it will be appreciated that the entire supporting structure, together with the central spring 22 is now embedded in a flexible plastic material to form a unit as shown in Fig. 7. Although this plastic material is flexible, it is not lively resilient, but rather is only passively resilient and more restful than lively rubber-like material.

This unit is now set in the sockets 20 of the dual flat springs 16 and 17 and attached to a wood base 25 by means of a series of hook bolts 26 as clearly shown in Fig. 8. The hook bolts 26 also attach an aluminum angle member 27 having a series of button-like projections 28 thereon by which the cover 29 is attached over a rubber-fibre upholstering member 30 interposed on top and over the sides of the member 27. By this structure, it will be appreciated that I have provided means whereby the members 21, 25, 29 and 30 may be readily separated for cleaning. Although it is possible to construct such a cushion embodying only the base wire 10, I find that a more durable and resilient cushion is obtained by employing the cushion supporting structure of lighter wire consisting of the members 11, 12, 14 and 15.

The bolt 19 securing the members 16, 17 and 18 also secures a yoke member 34 which resiliently supports a valve member 35 by means of a bolt 36 and an auxiliary spring 37. The valve 35 normally closes a circular opening 33 in the base 25 as will be readily appreciated when considering the action of the dual springs 16 and 17 together with the lighter auxiliary spring 37. When weight is applied to the supporting structure 21 as by a person seated on the cushion, the resilient spring member 23 bearing on the cup 18 and the dual springs 16 and 17 will force the valve 35 downwardly to permit air within the hollow interior of the cushion to escape through the valve opening 33 in the base 25. However, when no such weight is applied, the opening 32 will be sealed by the valve 35 by action of the auxiliary spring 37. From the above explanation, it will

be appreciated that I have provided a hollow cushion member which is normally sealed. It will be further appreciated that my light aluminum spring wire construction, combined with the light plastic material employed to embed the structure, provides a very light cushion that is extremely buoyant. This characteristic is of particular value for cushions employed in sea-going craft because such cushions might readily serve as life rafts or the like. It will be appreciated that the plastic material used herein is non-absorbent of moisture and this, combined with its very low specific gravity, further adds to the desirable light, buoyant characteristics. Where such buoyant characteristics are not needed the valve feature may be omitted.

My cushion structure may be readily attached to supporting structures such as aluminum tubes 31 by means of bolts 32 as clearly shown in Fig. 8. Although I have described a cushion such as employed for the seat of a chair, it will be appreciated that my structure is sufficiently flexible to permit cushions for the backs of chairs or for beds and the like.

Having thus described my invention, I now 25 claim as new:

1. In a cushion for the human body, an inverted box-like plastic member formed with relatively thin inwardly inclined side walls and an integral top section, an inverted resilient wire basket imbedded in the plastic member, the stiffness of the wire basket and its adhesion with the plastic walls providing a structure whereby the weight of the body is yieldably supported without uncomfortable contact pressure of the metallic wires on the body.

2. In a cushion as described in claim 1; the resilient wire basket including a base wire positioned closely adjacent the bottom of the plastic member, hook bolts inserted through the plastic material engaging said base wire and providing means attaching the plastic member to supporting structure.

3. In a cushion as specified in claim 1; a flat arched spring attached to the base wire and arched upwardly under the top section engaging and secured to a member depending from the top section and providing auxiliary support for the plastic member.

4. In a cushion for the human body, an inverted box-like plastic member, an inverted resilient wire basket including a base wire imbedded within the plastic member, the base wire being positioned closely adjacent the bottom of the plastic member, hook bolts inserted through the plastic material providing means attaching the plastic member to a supporting structure, a flat arched spring means attached to the base wire arching upwardly, a tubular plastic member attached to and depending from the inside center of the plastic member having a coiled spring imbedded therein to engage the arched spring means and to provide additional support.

5. In a cushion as specified in claim 4; said supporting structure comprising a base member in sealed attachment to the plastic member having a valve opening therein and a valve carried by the arched spring coacting with the valve seat around the opening providing structure whereby the hollow plastic member is sealed when the weight of the body is removed thereby providing a light weight cushion.

R. THUR SCHMIDT.
